UNITED STATES PATENT OFFICE.

JOSEPH BILLINGHAM AND CHARLES F. KAHLER, OF SCHENECTADY, NEW YORK.

VACUUM PISTON MECHANISM FOR LOCOMOTIVE DRIFTING-VALVES.

1,116,374.

Specification of Letters Patent. Patented Nov. 10, 1914.

Original application filed April 24, 1914, Serial No. 834,054. Divided and this application filed July 17, 1914. Serial No. 851,442.

To all whom it may concern:

Be it known that we, JOSEPH BILLINGHAM and CHARLES F. KAHLER, both of Schenectady, in the county of Schenectady and State of New York, have invented a certain new and useful Improvement in Vacuum Piston Mechanism for Locomotive Drifting-Valves, of which improvement the following is a specification.

10 In an application for Letters Patent for drifting valves for locomotives, filed by us April 24, 1914, Ser. No. 834,054, of which this application is a division, we have set forth an admission valve mechanism which 15 is controlled by a vacuum piston mechanism, which latter mechanism constitutes the subject matter of our present application.

The improvement claimed is hereinafter fully set forth.

20 The accompanying drawing is a vertical central section through a vacuum piston mechanism illustrating an embodiment of our invention.

In the practice of our invention we provide a vacuum piston chest or casing, 3, which is most conveniently located on one of the valve chests of the locomotive, in the position ordinarily occupied by the relief valve, the casing communicating, at its bottom, with the space within the valve chest on the admission side of the distribution valve, and being connected to the valve chest by a screw shank, 3^a, or through the intermediation of a ball joint, if preferred. An 30 open topped piston chamber, 3^b, is formed in the casing, 3, adjacent to a detachable cap, 3^c, which closes the top of the casing, and a central passage, 3^d, of substantially smaller diameter than the piston chamber, extends 35 downwardly therefrom in the casing, its lower end being closed by a screw plug, 3^e. An air port, 3^f, extends from the passage, 3^d, near its upper end, to the atmosphere; an exhaust port, 3^g, extends from the passage to the atmosphere, a short distance above the lower end of the passage; and a drain port, 3^h, leads out of the passage at or immediately adjoining its lower end. A 40 pressure inlet port, 3ⁱ, leads into the passage, 3^d, and a pressure outlet port, 3^k, leads out of said passage, below the pressure inlet port.

A fluid pressure supply pipe, 4, leads from any suitable source of fluid pressure supply, 55 as, for example, the main reservoir of the

brake apparatus of the locomotive, to a connection with the pressure inlet port, 3ⁱ, and a fluid pressure delivery pipe, 6, leads from a connection with the pressure outlet port, 3^k, to an admission valve mechanism, which, as it does not form part of our present invention, will not be herein described. A properly packed piston, 7, is fitted in the piston chamber, 3^b, and is secured on a piston stem, 7^a, which extends downwardly in the central passage, 3^d, of the casing, and carries three pistons, 8, 9, and 10, fitting the passage, 3^d, and making tight joints therewith by suitable packing. In the normal or inactive position of the parts, the piston, 8, stands between the piston chamber and the fluid pressure supply pipe; the piston, 9, between the fluid pressure supply pipe and the fluid pressure delivery pipe; and the piston, 10, below, and clear of, the exhaust port, 3^g.

The fluid pressure supply pipe, 4, may, instead of being connected to the main air reservoir, lead from any suitable location in the steam space of the boiler, and, in such case, is controlled by a suitable manually operable cock or valve. Either compressed air or steam may, without departure from the spirit and operative principle of our invention, be used for actuating the motor piston of the admission valve mechanism.

In the operation of the vacuum piston mechanism above described, the steam supply valve of the locomotive having been opened, and the locomotive running under steam, *i. e.* with its throttle valve open, the pistons, 7, 8, 9, and 10, of the vacuum piston mechanism, being subject to valve chest pressure, acting on the upper side of the piston, 7, remain in the ordinary normally seated positions shown in Fig. 3.

When the locomotive is "drifting" or running with its throttle closed, a partial vacuum will, by the reciprocation of the pistons in the cylinders, be formed therein, in the distribution valve chests on the admission side of the valves, and in the steam supply connections leading from the throttle valve to the distribution valve chests. The pressure previously acting on the upper side of the piston, 7, will be correspondingly reduced, and atmospheric pressure, acting on the lower side of said piston through the port, 3^g, will raise it, and the connected pistons, 8, 9, and 10, thereby bringing the fluid pressure supply pipe, 4, into communication

with the fluid pressure delivery pipe, 6. The pressure delivered from said pipe to the admission valve mechanism, will actuate said mechanism to effect the admission of steam 5 to the distribution valve chests and cylinders of the locomotive, which admission will continue during the drifting of the locomotive, as fully set forth in our application Ser. No. 834,054 aforesaid.

10 As soon as the cylinder pressure exceeds that of the atmosphere, the piston, 7, will be depressed, the air below it being exhausted through the port, 3^r; the piston, 9, will cut off communication between the fluid 15 pressure supply pipe, 4, and the fluid pressure delivery pipe, 6; and the fluid pressure in the latter pipe will be exhausted therefrom through the port, 3^s. The delivery of pressure to the admission valve mechanism, 20 through the pipe, 6, being thereby stopped, the supply of steam to the cylinders by the admission valve mechanism will be cut off.

We claim as our invention and desire to secure by Letters Patent:

25 A vacuum piston mechanism for locomotive drifting valves, comprising a casing or

chest having an open topped piston chamber, a removable cap closing the casing above said chamber, a passage extending from the opposite end of the casing to said chamber, a central passage of smaller diameter than said chamber, extending downwardly therefrom in the casing and closed at its lower end, fluid pressure supply and delivery ports opening into said passage, at different 30 levels, a piston fitting the piston chamber and fixed on a stem extending downwardly in the central passage, air passages leading into the piston chamber and into the central passage, respectively, and pistons fixed on the piston stem and fitting the central passage, said pistons controlling communication between the fluid pressure supply and delivery ports, between the piston chamber and the fluid pressure supply port, and between 40 the fluid pressure supply port and the atmosphere, respectively.
